UNITED STATES PATENT OFFICE.

FREDERICK WALTER NEVILLE, OF SALFORD, ENGLAND, ASSIGNOR TO J. W. JACKMAN & COMPANY LIMITED, OF VULCAN WORKS, SALFORD, ENGLAND.

TUMBLING BARREL.

Application filed November 30, 1925, Serial No. 72,416, and in Great Britain February 9, 1925.

This invention relates to tumbling barrels with or without a sand blast adapted to clean foundry castings after being taken from the moulds or other articles and its object is to provide for the extraction or removal from the barrel of the abrasive material, tailings and dust.

Tumbling barrels for foundry castings and other articles hitherto constructed have comprised a mechanically rotated, perforated drum into which a jet of abrasive is projected through one end on to articles contained by the barrel. Spent abrasive, foundry-sand, tailing and dust fall through the barrel perforations into an enclosing casing and are collected either pneumatically or mechanically the drum being supported and driven inside the casing by rollers which are consequently working under bad conditions with consequent heavy wear.

Another construction comprises a double barrel, the sand passing through perforations in the inner barrel being collected ready for re-use in the outer one.

According to the invention the barrel is constructed with a conical outer barrel which as it rotates will cause the loose material to flow towards one end, a cylindrical perforated inner barrel to receive the castings or articles to be cleaned, two end casings between which the barrels are clamped, one fitted with an inlet nozzle and the other with an outlet chamber rotating with the barrel to receive the loose material and discharge it through a hollow central trunnion or passage and an exterior chamber preferably perforated to act as a sieve or screw into which the spent abrasive material, sand and tailings are finally discharged.

The invention will be fully described with reference to the accompanying drawings.

Fig. 1 is a longitudinal section through the apparatus.

Fig. 2. is a transverse section.

Fig. 3 is a section through the end casing and chamber on line 3—3 Fig. 1.

Fig. 4. is a front elevation of steel end plate.

Fig. 5 is a sectional elevation of discharge end or cabinet when a suction system is applied to the apparatus.

The tumbler barrel is built up of a conical outer barrel A of sheet or plate metal and a cylindrical perforated inner barrel B, the barrels being clamped between and rotating

with end castings C and D by bolts or studs a, the end C being fitted with an injection nozzle E projecting through an aperture therein and the end D formed with a chamber d into which the spent abrasive sand and tailings are discharged from the outer barrel A.

The discharge chamber d is of annular or spiral form opening through a radial part d¹ into a hollow trunnion or passage d² and is fitted on its inner face with a steel plate F which closes the end of the inner barrel B but is provided with annular slots f, forming openings between the outer conical barrel A and the discharge chamber d. The discharge chamber or passage d—d¹ and the hollow trunnion d² are so shaped that material such as sand will be raised and fall through the radial passage d¹ and be delivered out of the front of the trunnion.

The perforated inner barrel B is fitted into a groove c¹ in the nozzle end casting C and into a groove f¹ in the end plate F metal to metal and the conical outer barrel is fitted into a groove c² in the nozzle end casting and into a groove f² in the plate F, the groove c² being preferably fitted with a rubber or leather ring to make a dust-tight seal at the nozzle end of the apparatus.

The barrels A and B are provided with apertures fitted with doors a¹, b¹ through which access may be had to the interior of the conical inner barrel B for placing and removing the articles to be cleaned.

The doors comprise an inner perforated plate b¹ conforming to the contour of the barrel B and an outer plate a¹ resting when in position on the barrel A, the plates being connected together by distance bolts and clamped on to the barrel A by bolts and nuts.

A coarse conical screen G designed to separate the finer sand and abrasive from the tailings is affixed to the exterior of the delivery end casting D to receive the material from the discharge passage and trunnion d¹, and an outer conical casing G¹ preferably revolving with it is fitted around the conical screen G. The fine or screened material is delivered from the casing G¹ to a chute g¹ and the lumps and tailing are delivered from the screen G to the chute g, situated in a dust exhaust box H.

An injector nozzle E is mounted on a bracket at the end of the barrel and a dust shield K is affixed to the face of the nozzle-

end casting C surrounding the aperture and rotating in close proximity to a flange e on the nozzle E. Pitched near the periphery of the dust shield K in the casting C a ring 5 of holes k is drilled obliquely to the axle of the barrel to permit any abrasive that may splash back through the nozzle opening e to be returned to the barrel.

The end castings C and D are turned cylindrical on their peripheries to form treads which are supported upon and driven by four rollers M keyed to two shafts m rotating in bearings on the standards M¹. To the standard M¹ a gear case M⁴ is fixed 15 carrying three gears M², M³, M², one "gear" wheel M² keyed to each of the shafts m with an intermediate gear wheel M³ between them. The gear wheel M² is driven by a pulley M⁵.

20 When the apparatus is adapted to be used with direct pressure sand blast the dust exhaust box H is divided into two compartments by vertical partition h¹ with a sloping base or chute g¹ leading to a hole in the side of the dust box. The base of the dust box H is inclined to lead to a chute or outlet g. The top of the box is connected by a pipe h to a dust exhaust fan. The exhaust box H is mounted on one of the 25 pillars M¹.

When the apparatus is adapted to be used with suction system sand blast a cabinet N (see Fig. 5) is substituted for the dust box H in which the abrasive instead of being 35 delivered down a channel chute is collected in a central chamber n at the bottom of which a suction system sand valve n¹ is fitted while tailings pass over to the compartment n².

40 In operation abrasive is injected through the nozzle E on to objects placed in the perforated inner barrel B and as the barrels rotate the dust, tailings and abrasive fall through the perforations into the conical outer barrel A and slide down through the slots f in the plate F into the discharge chamber d in the end casting D, and are discharged from the hollow trunnion d² into the conical screen G. The tailings and 45 lumps are delivered over the end of the screen G while the screened and cleaned abrasive falls on to the casing G¹ and is delivered over the end on to the chute g, 50

being delivered usually from there into the sand blast apparatus to be returned again 55 to the nozzle E. The fan connected to the exhaust pipe h draws air through the barrels A and B from the nozzle E (including air injected by the nozzle) and also through the discharge chute g thus preventing dust 60 appearing outside the barrels. The discharge chute g and the dust box H are so proportioned that dust not taken up by the fan is deposited in the box clear of the abrasive and may be removed with the tailings 65 through the discharge opening or chute g¹ which is normally connected to the air-tight bag or box.

What I claim as my invention and desire to protect by Letters Patent is:—

70 1. A tumbling barrel for cleaning foundry castings comprising the combination with a perforated inner barrel to receive the castings, of a conical outer barrel to collect the fine material as it falls through the perforations, a casting at one end with an aperture through which abrasive material may be injected, a casting at the other end provided with a discharge chamber to receive the spent abrasive tailings and dust from the conical barrel and a hollow trunnion leading from the discharge chamber through which the tailings and dust are discharged.

75 2. A tumbling barrel for cleaning foundry castings comprising the combination with a conical outer barrel of a cylindrical perforated inner barrel to receive the castings to be cleaned through the perforations of which spent abrasive tailings and dust fall into the outer barrel, a casting at one end of the barrels, an abrasive injector therein, a casting at the other end of the barrels formed with discharge passages to receive the spent abrasive, tailings and dust from the conical barrel and a hollow trunnion therein through 80 which the spent abrasive tailings and dust are discharged, a dust box fitted over the discharge end of the barrels and a rotary screen attached to the discharge end casting within 85 the dust box to separate the finer used abrasive from the tailings.

90 In testimony whereof I have hereunto set my hand.

F. W. NEVILLE.
